UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,089,446.

Specification of Letters Patent. Patented Mar. 10, 1914.

Application filed August 22, 1913. Serial No. 786,091.

To all whom it may concern:

Be it known that I, HERBERT H. STEELE, a citizen of the United States, and resident of Marcellus, in the county of Onondaga and State of New York, have invented certain new and useful Improvements in Type-Writing Machines, of which the following is a specification.

My invention relates to key operated devices for typewriting machines and its general object is to provide new and improved key operated devices for controlling movable parts and particularly the stop setting and stop retracting devices of key set tabulating mechanism, especially when such mechanism is of the magazine style.

Another object of the invention is to provide novel full-stroke devices for key set tabulating mechanism.

Another object is to provide a simplified and improved construction of stop magazine or container.

Another object is to improve the construction and mode of operation of key set tabulating mechanisms of the magazine style.

To the above and other ends which will hereinafter appear, my invention consists in the features of construction, combinations of devices and arrangements of parts hereinafter described and particularly pointed out in the claims.

In carrying out my invention in the present instance I have, as shown, applied it to a No. 3 Monarch typewriting machine and to key set tabulating mechanism of the character disclosed in my prior Patent No. 1,037,076 of August 27, 1912, although it is to be understood that the principles of the invention may readily be embodied in other styles of writing machines and of tabulating mechanism.

In the accompanying drawings, Figure 1 is a fragmentary side elevation, partly in section, of a Monarch typewriting machine embodying my invention, parts of the machine being omitted and parts broken away. Fig. 2 is a fragmentary side elevation of certain of the escapement devices and stop ejecting devices shown in Fig. 1. Fig. 3 is a vertical sectional view taken on a plane indicated by the broken dotted line $x-x$ in Fig. 1. Figs. 4, 5 and 6 are enlarged views illustrating the details and operation of the novel key mechanism, Fig. 4 being a vertical section taken through the key

stems, Fig. 5 partly in vertical section and Fig. 6 in side elevation. Fig. 6^a is a fragmentary front view of the left-hand front corner post and associate parts. Fig. 7 is a top plan view showing an improved construction of stop magazine or holder comprising two parts. Fig. 8 is a transverse sectional view taken on a plane indicated by the dotted line y in Fig. 7 and looking in the direction of the arrow at said line. Figs. 9 and 10 are respectively side and end elevations of the main part of the stop magazine holder shown in Fig. 7. Figs. 11 and 12 are corresponding views of the other part of the stop magazine.

As shown in Figs. 1 and 2, the main frame comprises a base 1, posts 2 and a top plate 3 supporting goose-neck standards 4 to which are fixed grooved track-ways 5 and 6 co-operating through anti-friction balls 7 with the grooved rear bar 8 of a platen carrier or carriage which further includes forwardly extending end bars 9. The end bars 9 provide bearings for a rotary platen 10 with the front face whereof co-operate type bars (not shown) which are supported on a shifting segment and are operated by trains of devices each comprising a sub-lever 11 pivotally connected with a key lever 12, the set of key levers being arranged within the base of the machine. The carriage is constantly urged leftward by a motor or spring drum (not shown). Pivoted to the end bars 9 are arms 13^a which support a spring-pressed feed rack 13 that meshes with a pinion 14 operatively connected to a toothed escapement wheel 15. Co-operative with the escapement wheel are dogs 16 mounted on a dog rocker 17 which is pivotally supported on a bracket 18. A link 19 connects the dog rocker with a pivoted universal bar frame 20 carrying a universal bar proper 20^a which underlies the key levers 12.

The denominational tabulating mechanism of the machine comprises a set of upright denominational stop levers 21 pivoted at 22 in a frame 23 secured to the main frame. The upper end portions of the levers 21 are curved forward terminating in denominational stops proper 24, said stops being arranged a letter space distance apart lengthwise of the carriage and being adapted when actuated or projected horizontally forward to co-operate with column stops hereinafter described. The actuating de-

5 vices for the stop levers 21 comprise slide bars 25 which bear at their rear end portions on a part of the frame 23 and are adapted to push against the lower arms of 10 the levers 21. The forward ends of the bars 25 bear slidably in a detachable supporting frame 20 and are adapted to be actuated by arms 27 secured to short rock shafts 28 bearing in upright portions of the frame 26. 15 Fixed to the rock shafts 28 are levers 29 provided with denominational tabulator keys 30. When a key 30 is actuated it rocks the associate shaft 28, causing the crank arm 27 to slide the bar 25 rearward, the 20 latter swinging the associate lever 21 on its pivot and projecting the stop 24 into the path of the column stops.

25 The actuation of one of the stop levers 21 operates carriage releasing devices comprising a universal bail 31 having end portions 32 pivoted at 33 to the frame 23. One of the end portions has an extension 32^a which is connected by a link 34 to one arm of a lever 35 pivoted at 36 to a stationary bracket 37, 30 said lever arm being connected at its end with a lifter 38 which has shoe portions underlying the feed rack 13. When the universal bail 31 is swung rearward by one of the stop levers 21 said bail operates through 35 the train of connecting devices to raise the lifter 38, separating the feed rack from the pinion 14 and permitting the carriage to be drawn rapidly leftward by the carriage motor. The usual restoring springs are provided for the carriage releasing and denominational stop mechanisms.

40 Projecting rearward from the slide bar 8 are arms 39 which provide a support for a column stop bar 40 that is toothed at its front and rear faces to form notches for receiving column stops 41 that are retained in place on the stop bar by a spring pressed locking rod 40^a housed within a groove in the front face of the stop bar.

45 The stops 41 when not in use are adapted to be housed within a stop magazine or holder of novel construction comprising essentially as is clear from Figs. 7 to 12, two U-shaped parts 42 and 43, the part 42 being 50 shown detached in Figs. 9 and 10 and the part 43 being similarly shown in Figs. 11 and 12. The two parts 42 and 43 are made of cast metal of suitable composition and all machine work is eliminated, thus greatly reducing the cost of manufacture. The part 42 which may be said to be the main part 55 comprises a U-shaped body portion 44 and a head 45 as well as a barrel or cylindrical portion 46 at the opposite end from the head. 60 The part 43 is U-shaped in cross section and forms the downward sides and floor or bottom of the magazine proper. The two parts after being cast are ready for assembling without requiring any finishing or other additional work; and when assembled or in-

terseated as illustrated in Figs. 7 and 8 are detachably secured together by screws 47, said screws passing loosely through holes in the edge portions of the part 42 and being received in tapped holes formed in lugs 48 on the part 43. The two-part magazine after being assembled may be adjustably attached to the machine frame by screws 49 passing through slots 50 formed in lateral ears 42^a on the part 42, said screws engaging in tapped openings in the carriage rail 5. The part 42 has vertical guide ways 51 and 52 cast in its head 45. These guide ways receive respectively the slidable stop ejector and stop retractor hereinafter described and have been found in practice to provide for a smooth and effective control and guidance of these slidable parts or pieces. Further the barrel portion 46 is open at its right-hand end and is slightly flared to receive and 85 fixedly hold by a driving fit or otherwise a tapered plug or end piece 53 which is rigidly connected to a supporting rod 54, said rod and said plug being preferably made of steel.

90 The column stops 41 are arranged or stored on the support or rod 54 as in my prior patent aforesaid, being pressed outward along the rod 54 by a spring pressed follower (not shown), and are adapted to 95 be forced downward off the rod and projected through a slot-way or opening 55 formed between the edge of the floor portion 56 of the part 43 and the inner face of the head 45. The magazine is arranged directly above the column stop bar and the slot-way 55 is above the top of the bar so that when the column stops are ejected through the slot they will be forced downward to engage with the notches of the stop 100 bar. The ejecting or stop controlling devices comprise, as disclosed in my prior patent aforesaid, a device, element or slide 105 57 which is arranged in and guided by the groove 51 in the head 45. A retractor element or slide 58 fits into the parallel guiding groove 52 and is adapted to retract the stops 41 from the stop bar 42 into the magazine, said retractor being arranged at the forward side of the stop bar and when in 110 normal position extending below the stop bar and terminating at its lower end in a lug or toe piece 59 which underlies the forward portions of the set column stops. The 115 ejector 57 is operated by a train of key controlled devices comprising an upright angular link 60 connected through a shouldered screw 61, with the ejector 57, the lower end of said link being pivotally connected with a crank arm 62 extending rearward from a 120 rock shaft 63, said crank arm being provided with a hub 64 which fits over the inner end of the rock shaft and is pinned thereto. The rock shaft bears at its right-hand end in the 125 forwardly turned ears 65 of a bracket 66 130

which is secured by screws 67 to the bracket 18. The left-hand end of the rock shaft bears in an angular bracket 68 screwed to the left-hand rear corner post 2 and has fixed to it 5 an upwardly extending crank arm 69 from which extends forward a rod or link 70. The construction as thus far described corresponds with that found in my prior patent aforesaid but the rod 70 instead of being 10 provided with a rigid key at its front end as in said prior construction is associated with novel devices to be presently described. The retractor 58 is operative by a similar train of stop controlling devices, said retractor 15 being provided with a lateral shouldered screw 71 which pivotally supports the upper end of a link 72, the lower end of said link being pivotally connected to a crank arm 73 extending rearward from a sleeve 74 to the right-hand end of which said crank arm is fixed. The sleeve surrounds and bears loosely on the rock shaft 63, being confined between the crank arms 73 and 69. Fixed to the left-hand end of the sleeve 74 20 is a downwardly extending crank arm 75 to which is connected a forwardly extending 25 rod or like 76.

The rods, elements or devices 70 and 76 bear near their forward ends in ears 77 bent 30 laterally from a bracket 78 which is secured to the left-hand guide post 79 of the type bar supporting segment. Draw springs 80 and 81 anchored at their forward ends to a pin 82 on the post 79 are connected at their 35 rear ends respectively to the crank arms 69 and 75 and tend to restore said crank arms and the connected trains of devices after operation to the normal position shown in Fig. 1.

40 In practice heretofore it has been found that the column stops during the stop ejecting and stop retracting operations were liable because of faulty or insufficient operation of the actuating keys to be arrested in 45 the magazine entrance way when partly on and partly off the column stop bar, the stop bar and the magazine constituting relatively movable elements or stop supporting devices on one of which, in the present instance the 50 magazine, the column stops are normally mounted and from which said column stops are adapted to be moved to and upon the other of said elements, in this case the column stop bar. The operator not being aware of 55 this defective operation would thereafter attempt to move the carriage to the right or left and the result would sometimes be that the carriage would become jammed fast by the partially ejected or retracted stop, causing 60 considerable trouble and annoyance before it could be freed. Various means for obviating this defect have been devised heretofore including full-stroke devices but the 65 plans heretofore suggested have all been open to objection of some sort, some of the

suggested devices being complicated in construction and others being found not easy of application. For example, it has been found difficult to adjust and adapt full-stroke devices of the usual character because 70 of the short motion which is imparted to the stop set and stop retracting keys. My present invention is designed to overcome the 75 defects and objections above noted and others in connection with key operated mechanism, and to this end I provide novel power storing and trip mechanism, associating with each key in the present instance a power device compression spring in which is stored up by the key action efficient power 80 to operate the devices associated with said key. To insure a full movement of such devices the operator must depress the key the full distance, as otherwise the key returns without accomplishing anything, due to the 85 fact that the trip which releases the compression or power spring is only operated at or near the end of the key action. The result is that a column stop cannot be ejected or withdrawn only part of the distance, the operator 90 being unable to shift the stop except through releasing the compression spring and as soon as this occurs the devices are withdrawn from the control of the operator, the spring 95 performing the operation of setting or retracting the stop. Of course, it is only necessary to store sufficient power in the spring to insure that the stop setting or retracting movement under its control shall be full and complete. It will be understood that the intermittently acting power springs are opposed by the constantly acting draw springs 100 80 and 81 and to be effective must overcome said opposing draw springs.

105 Referring more in detail to the preferred embodiment of my invention and which is clearly illustrated in Figs. 1 and 4 to 6, the forward end portion of each of the actuators, members or slidable rods 70 and 76 supports a hollow key stem 83, each key stem being 110 bored out as indicated at 84 to fit over and slidably engage or loosely connect with its associate rod, member or stop controlling device. The key stems or devices 83 slidably engage in bearing openings in the parallel 115 walls 2^a and 2^b of the left-hand front corner post 2 and also pass through holes in a plate 85 which is clamped between the front of said corner post and the usual front plate 86 by the screws 87, the front plate being cut 120 away as indicated at 88 where the key stems pass through the plate 85. Forward of the front plate the stems 83 are provided with finger keys or buttons, the upper key 89 being marked with suitable indicating devices as the word "Set," and the lower key 90 having also suitable indicating marks as "Clear." Behind the post wall 2^a, each of the rods or members 70 and 76 is surrounded 125 by and supports a cylindrical barrel or hous- 130

ing 91, each barrel being open at its front end which normally abuts against the rear face of the corner post and terminating at the rear in a hub portion 92 which receives a set screw 93 that secures the barrel to its supporting rod. Within the bore 94 of each barrel is arranged a coiled compressible spring or power device 95, said spring surrounding and being mounted on the associate supporting rod and being confined between the bottom face of the bore 94 and a collar 96 which is adjustably secured on the inner end of the associate key stem 83 which is threaded for the purpose as indicated at 97, said collar being formed with a corresponding tapped opening. The collar, which constitutes means for compressing or storing power in the associate power spring, is maintained set in proper position on its key stem by a check nut 98 which is threaded on the portion 97 forward of the collar and is screwed up tight against said collar after it has been properly adjusted. A screw stop or arresting device 99 is threaded into each barrel 91 and projects partway into the bore thereof in position to coöperate with the check nut or arresting device 98 to limit the forward movement of the key stem 83 which supports said check nut.

It will be understood that the rods 70 and 76 are moved forward by the associate restoring springs 80 and 81 until arrested by the contact of the barrels or arresting devices 91 with the corner post 2, thus determining the limit of movement and the normal position of the rods and the barrels supported thereon as well as of the screw stops 99. Also it will be understood that the nuts 98 contacting with said screw stops limit the forward movements of the key stems when they are being pushed forward on and relatively to their supporting rods and thereby determine the normal positions of said key stems. Preferably the power springs are practically inert at the moment of arrest. Each collar 96 is provided with a lug or extension 96^a which projects outward through a slot 100 cut or otherwise formed longitudinally in the barrel 91, said slot being of sufficient width to permit sliding movements of the lug 96^a longitudinally thereof. From Fig. 4 it will be plain that the lug 96^a of the upper collar projects downward through the associate slot 100, which slot is formed in the under side of the barrel 91; while the lug 96^a of the lower collar projects upward through the associate slot 100 and the lower barrel 91, the last named slot being formed in the upper side of said barrel. The lugs 96^a constitute means for releasing detent members which hold the barrels 91 against substantial rearward movement and prevent actuation of the slidable rods. In the present instance said detent members are in the form of op-

ositely arranged arms 101 which extend forward one above the other between the barrels 91, each of said arms being pivoted near its rear end on a screw 102 which is secured to the side of the bracket 78 between the ears 77. Each of said detent arms 101 is provided with a locking shoulder 103 which coöperates with the annular shoulder 104 formed between the body portion of the associate barrel 91 and its hub portion 92, 70 said hub portion, as is shown, being of lesser diameter. Forward of the shoulder 104 each arm 101 terminates in a pointed head or end portion 105, said end portion projecting into the associate slot 100 and 75 having an inclined or cam edge 105^a which extends downward out of the slot and into the path of the associate lug 96^a which, as shown, is rounded for coöperation with said inclined edge, the inclined edge terminating 80 at the forward end of the portion 105 at a slightly greater distance from the face of the periphery of the barrel than does the lug 96^a. Near their ends the arms 101 are provided with oppositely projecting lugs 90 106 around which is coiled a spring 107. The spring acts on both arms 101, tending to swing them apart and force their end portions 105 within the associate slots 100, this movement being limited in any suitable 95 way as by the engagement of the end portions 105 with the springs 95. At this time or normally the ends of the lugs 106 are separated as shown in Fig. 4.

In operation when the stop set key 89 100 is pressed in its motion will be transmitted through the collar 96 and spring 95 to the barrel 91 which will be moved slightly rearward until arrested by the engagement of the shoulder 104 with the shoulder 103, 105 these shoulders being normally slightly separated. After this slight initial movement the barrel 91 will remain motionless as the key 89 is pushed in and consequently the spring 95 will be compressed by the collar 96 which will continue to move rearward within the barrel, the key stem 83 at the same time sliding rearward on the rod 70 until the lug 96^a engages with the cam edge 105^a, forcing the head 105 downward 110 and swinging the arm 101 on its pivot, this swinging movement continuing until the shoulder 104 disengages from the shoulder 103, thereby releasing the barrel 91 and the rod 70. As soon as the barrel is released 115 the compressed spring 95 forces it and the rod 70 rearward and the power stored in the spring is sufficient to overcome the spring 80 and to actuate the train of stop controlling or ejecting devices comprising the 120 crank arm 69, rock shaft 63, crank arm 62 and link 70, forcing the ejector 57 downward and ejecting the underlying stop within the magazine, said stop being pushed 125 downward by the ejector through the mouth 130

of the magazine and on to the column stop bar. It will be apparent that as soon as the detent device or shoulder 104 frees the barrel 91 the ejector mechanism will be taken out of the control of the finger key 89 and the entire ejecting operation proper will be performed by the spring 95, the function of the key 89 being first to compress said spring and then to release it so that it may perform its work. When the key 89 is released the parts will be restored to normal position by the springs 80 and 95. Similarly, a retracting operation is effected by actuating the clearing key 90 which is pressed in first, compressing the associate spring 95 and then through the lug 96^a releasing or tripping the arm 101 to permit the compressed spring, acting through the barrel 91 and rod 76, to actuate the retracting devices and cause the retractor 58 to raise the column stop that is in register therewith off the stop bar and force it through the magazine mouth into the magazine. In Fig. 5 the parts of the retracting mechanism are shown near the end of the operation of the key 90 and just as the release of the compressed spring 95 is about to take place.

The lugs 106 are adapted to coöperate with each other to act as safety devices to prevent the simultaneous effective operation of the keys 89 and 90 as will best be understood from Fig. 6. Said lugs are of such length that their ends will engage if both keys be pressed in together and as a result of such engagement the arms 101 will be arrested before the shoulders 103 have moved far enough to release their associate barrels 91.

As a further measure of precaution improved and simplified means are provided for automatically spacing the carriage after a stop ejecting operation, thus preventing one stop from being ejected on to another with the possibility of jamming the ejecting mechanism and the carriage. Said improved means comprise as illustrated in Figs. 1 and 2 an angular member or arm 108 which is secured by a screw 109 or otherwise to the link 19 of the escapement mechanism. The arm 108 extends rearwardly and is off-set toward the left, terminating in an upwardly extending portion 110 which is provided with a laterally extending horizontal lip or ledge 111 that underlies the crank arm 62, being normally separated therefrom as shown in Fig. 1. When the ejecting devices are operated the arm 62 will swing downward toward the end of its movement far enough to contact with the lip 111 and force it downward, thus forcing downward the link 19 with which said lip and the arm 108 are rigidly connected, thereby operating the escapement devices and causing a letter space

movement of the carriage toward the left after the stop has been ejected, the ejected stop being thus carried out of register with the magazine slot-way.

Various changes may be made without departing from the spirit and scope of my invention.

What I claim as new and desire to secure, by Letters Patent, is:—

1. In a typewriting machine and in tabulating mechanism, the combination of column stops, a stop magazine, a column stop bar, a stop ejector, a stop retractor, lever members, links connecting said lever members with said ejector and retractor, rods connected to said lever members, key stems slidably connected with said rods, power springs mounted on said rods, said springs being compressible by devices operative by said key stems, detent devices normally preventing effective actuation of said rods by said springs, and means connected with said key stems for rendering said detent devices ineffective.

2. In a typewriting machine and in tabulating mechanism, the combination of column stops, a stop magazine, a column stop bar, a stop ejector, a stop retractor, lever members, links connecting said lever members with said ejector and retractor, rods connected to said lever members, key stems slidably connected with said rods, springs mounted on said rods, said springs being compressible by devices operative by said key stems, detent devices normally preventing effective actuation of said rods by said springs, means connected with said key stems for rendering said detent devices ineffective, and means for preventing simultaneous effective operation of said key stems.

3. In a typewriting machine and in tabulating mechanism, the combination of a stop magazine, a column stop bar, a stop ejector for ejecting said stops from said magazine on to said stop bar, a train of devices connected to said ejector and comprising a link, a lever member and a rod, a housing on said rod, a power spring within said housing, a detent effective on said rod, a key stem connected with said rod, and devices connected with said key stem for storing power in said power spring and for releasing said detent.

4. In a typewriting machine and in tabulating mechanism, the combination of a stop bar, column stops thereon, a stop magazine, a stop retractor for retracting the stops from said stop bar into said magazine, a train of devices connected with said retractor and comprising a link, a lever member and a rod, a housing on said rod, a power spring within said housing, a detent normally preventing effective actuation of said rod, a key stem connected with said rod, and devices

connected with said key stem for storing power in said power spring and for releasing said detent.

5. In a typewriting machine and in tabulating mechanism, the combination of a stop setting device, a train of devices connected to said setting device comprising a link, a lever member and a rod, a housing on said rod, a power spring within said housing, a 10 detent for said rod normally in effective position, a key stem slidable on said rod, and devices connected with said key stem for storing power in said spring and for releasing said detent.

15. In a typewriting machine and in tabulating mechanism, the combination of a stop setting device, a train of devices connected thereto including a slidable member, a housing on said member, a power spring within 20 said housing, a detent for said member, a key connected with said member, and devices connected with said key for storing power in said power spring and for releasing said detent.

25. In a typewriting machine and in tabulating mechanism, the combination of a plurality of stop controlling devices, trains of devices connected thereto, each train comprising a slidable member, power springs for actuating said members, detent devices for said members, said detent devices being normally in effective position, keys connected with said members, and devices connected with said keys for storing power in said 30 springs and for releasing said detent devices, one of said keys being associated with one of said stop controlling devices to cause the latter to set stops in effective position and the other key being associated with the 35 other of said stop controlling devices to cause it to retract stops from effective position.

40. In a typewriting machine and in tabulating mechanism, the combination of a plurality of stop controlling devices, trains of devices connected thereto, each train comprising a slidable member, power springs for actuating said members, detent devices for said members, keys connected with said 45 members, and devices connected with said keys for storing power in said springs and for releasing said detent devices, one of said keys being effective to cause one stop controlling device to set stops in effective position and the other key being effective to cause the other stop controlling device to retract stops from effective position, and means for preventing simultaneous effective operation of said keys.

45. In a typewriting machine and in tabulating mechanism, the combination of a stop controlling device, actuating mechanism connected therewith comprising a slide rod, a barrel fixed thereto, a power spring coiled around said rod and housed within said bar-

rel, a spring pressed detent effective on said barrel, a key stem slidable on said rod, a device connected to said stem and operative on said spring to compress it, and a device connected with said stem for thereafter releasing said detent. 70

5. In a typewriting machine and in tabulating mechanism, the combination of a stop controlling device, actuating mechanism connected therewith comprising a slide rod, a power spring coiled around said rod, a key stem slidable on said rod, and means effective on said spring to compress it and to release it after compression so that it may expand and actuate said rod. 75

15. In a typewriting machine and in tabulating mechanism, the combination of a stop controlling device, actuating mechanism connected therewith comprising a slide rod, a barrel fixed thereto, a power spring housed within said barrel, a pivoted spring pressed detent member for said rod normally projecting into a slot-way in said barrel, a key stem slidable on said rod, a collar on said 80 detent effective to compress said spring, and a projection on said collar extending into said slot and effective to release said detent. 90

10. In a typewriting machine and in tabulating mechanism, the combination of a stop controlling device, actuating mechanism connected therewith comprising a slide rod, a barrel fixed thereto, means for affording an adjustment of said barrel on said rod, a power spring within said barrel, a detent for said rod, a key stem slidably connected with said rod, a collar adjustable on said stem and effective to compress said spring, said collar being provided with a part for releasing said detent, a stop for said collar connected with said barrel, and a fixed abutment with which 105 said barrel normally co-operates. 100

13. In a typewriting machine and in tabulating mechanism, the combination of two relatively movable elements, a stop normally mounted on one of said elements but controllable so that it may be moved to and upon the other of said elements, key operated stop controlling devices, two opposing springs, one of said springs being effective to restore certain members of said train to normal position, adjustable stop devices effective to determine said normal position, devices for storing power in said second spring and rendering it effective to overcome the first spring, and means for affording adjustment of certain of said last recited devices. 110 115

14. In a typewriting machine and in tabulating mechanism, the combination of two relatively movable elements, a tabulator stop normally mounted on one of said elements but movable therefrom on to the other of said elements, tabulator stop actuating mechanism, opposing springs connected therewith, one constantly acting and one inter- 120 125 130

mittent, and devices for rendering said intermittent spring effective to overcome the constantly acting spring.

15. In a typewriting machine and in tabulating mechanism, the combination of two relatively movable elements, a stop normally mounted on one of said elements but controllable so that it may be moved to and upon the other of said elements, a stop controlling device, actuating mechanism connected therewith comprising a slidable member, a power device connected to said slid- 5 able member, a key, and means operative by said key for storing power in said power device and for rendering said power effective on said slidable member.

16. In a typewriting machine and in tabulating mechanism, the combination of two relatively movable elements, a stop normally mounted on one of said elements but controllable so that it may be moved to and upon the other of said elements, a stop controlling device, actuating mechanism connected therewith comprising a push rod, a power spring supported by and effective on 10 said push rod, a detent for said push rod, and key controlled means for storing power in said spring and for thereafter releasing said detent.

17. In a typewriting machine and in tabulating mechanism, the combination of two relatively movable elements, a stop normally mounted on one of said elements but controllable so that it may be moved to and upon the other of said elements, a stop controlling element, a power device, a key, and means controlled by said key for rendering said power device effective to move said stop controlling element, said power device being 25 normally ineffective on said stop controlling element.

18. In a typewriting machine and in tabulating mechanism, the combination of two relatively movable elements, a stop normally mounted on one of said elements but controllable so that it may be moved to and upon the other of said elements, a tabulator stop controlling device, key controlled power storing means, and means for rendering the stored power effective on said stop controlling device.

19. In a typewriting machine and in tabulating mechanism, the combination of two relatively movable elements, a stop normally mounted on one of said elements but controllable so that it may be moved to and upon the other of said elements, a tabulator stop controlling element, a train of devices connected thereto, a detent associated with certain of said devices and normally positioned to prevent effective operation of said train of devices, a power spring connected to certain of said devices and normally ineffective, and key controlled means for storing power in said spring and for thereafter re-

leasing said detent to render said power effective.

20. In a typewriting machine and in tabulating mechanism, the combination of two relatively movable elements, a stop normally mounted on one of said elements but controllable so that it may be moved to and upon the other of said elements, a tabulator stop controlling element, a train of devices connected thereto, a spring, arresting devices for limiting the movement of said train of devices under the action of said spring and determining the normal position of said train, a second spring connected to certain of said devices, and key controlled means for storing power in said second spring and overcoming the first recited spring.

21. In a typewriting machine and in tabulating mechanism, the combination of two relatively movable elements, a stop normally mounted on one of said elements but controllable so that it may be moved to and upon the other of said elements, a tabulator stop controlling element, a train of devices connected thereto, a spring, arresting devices for limiting the movement and determining the normal position of said train, a detent for preventing the effective operation of said train of devices, a power spring connected to certain of said devices and normally weaker than the first spring, and key controlled means for storing power in said power spring and for thereafter releasing said detent to render said power spring effective.

22. In a typewriting machine and in tabulating mechanism, the combination of two relatively movable elements, a stop normally mounted on one of said elements but controllable so that it may be moved to and upon the other of said elements, a tabulator stop controlling element, a train of devices connected thereto, a spring, arresting devices for limiting the movement of said train of devices under the action of said spring and determining the normal position of said train, a power spring connected to certain of said devices but normally substantially inert, and key controlled means for rendering said power spring effective to overcome said first recited spring and actuate said stop controlling element.

23. In a typewriting machine and in tabulating mechanism, the combination of two relatively movable elements, a stop normally mounted on one of said elements but controllable so that it may be moved to and upon the other of said elements, a stop controlling element, a train of devices connected thereto, a restoring spring for said train, arresting devices for limiting the movement of said train under the action of said spring, means for affording an adjustment of said arresting devices to vary the normal position of said train, a second

spring, and key controlled means for causing said second spring to act in opposition to and overcome said first recited spring.

24. In a typewriting machine and in tabulating mechanism, the combination of two relatively movable elements, a stop normally mounted on one of said elements but controllable so that it may be moved to and upon the other of said elements, a stop controlling element, a train of devices connected thereto, a restoring spring for said train, arresting devices for limiting the movement of said train under the action of said spring, means for affording an adjustment of said arresting devices to vary the normal position of said train, a second spring connected to certain of said train of devices, key controlled devices operative on said second spring to store power therein, and means for affording variation in the normal position of certain of said key controlled devices to vary the action thereof on said second spring.

25. In a typewriting machine and in tabulating mechanism, the combination of two relatively movable stop supporting devices, a stop normally mounted on one of said stop supporting devices but movable (therefrom to and upon the other of said stop supporting devices, stop controlling devices comprising a movable element, arresting means for said element, a restoring spring connected to said element and normally effective to maintain said arresting means in engagement, detent devices normally preventing operation of said stop controlling devices, a power spring effective to move said element in opposition to said restoring spring but normally ineffective, and key actuated means for rendering said power spring effective to overcome said restoring spring.

26. In a typewriting machine and in tabulating mechanism, the combination of stop controlling devices comprising a movable element, arresting means for said element, a restoring spring effective on said element, a power spring for moving said element in opposition to said restoring spring, a key stem connected to said element, a collar on said key stem effective on said power spring to store power therein, and means for affording adjustment of said collar to vary its effect on said power spring.

27. In a typewriting machine and in tabulating mechanism, the combination of stop controlling devices comprising a movable element, arresting means for said element, a restoring spring effective on said element, detent devices, a power spring for moving said element in opposition to said restoring spring, a key stem connected to said element, a collar on said key stem for compressing said spring, said collar being provided with a part for releasing said detent, and means

for adjustably securing said collar on said key stem.

28. In a typewriting machine and in tabulating mechanism, the combination of stop actuating devices including an element or rod, a spring normally effective to urge said rod in one direction, restraining means for normally preventing effective movement of said rod in the opposite direction, a power spring normally substantially inert, a key loosely connected with said rod, and means operative by said key for rendering said power spring effective to overcome the first recited spring and for rendering said restraining means inoperative.

29. In a typewriting machine and in tabulating mechanism, the combination of a plurality of tabulator stop controlling elements, trains of devices one connected to each element, detents, one associated with certain of the devices in each train and normally positioned to prevent effective operation of said train, power springs, one connected to certain of the devices in each train, means comprising a plurality of keys one for each train, said means being effective to store power in said springs and to release said detents to render said power effective, and means for preventing the simultaneous effective operation of said keys.

30. In a typewriting machine and in tabulating mechanism, the combination of a plurality of tabulator stop controlling elements, trains of devices one connected to each element, detents, one associated with certain of the devices in each train and normally positioned to prevent effective operation of said train, power springs, one connected to certain of the devices in each train, means comprising a plurality of keys one for each train, said means being effective to store power in said springs and to release said detents to render said power effective, and means for preventing the simultaneous effective operation of said keys.

31. In a typewriting machine and in tabulating mechanism, the combination of a carriage, column stops, a stop magazine element, a stop bar element, one of said elements being mounted on said carriage, stop controlling devices for moving said column stops between said elements, escapement devices for said carriage, and a projection on certain of said escapement devices extending into the path of certain of said stop controlling devices and operative thereby to actuate the escapement devices.

32. In a typewriting machine and in tabulating mechanism, the combination of a car-

- riage, column stops, a stop magazine element, a stop bar element, one of said elements being mounted on said carriage, stop controlling devices for moving said column stops between said elements including a lever member, carriage escapement devices comprising a link, and an arm secured to said link and extending into the path of said lever member, said arm being operative 5 by said lever member to automatically actuate the escapement when said stop controlling devices are operated.
33. In a typewriting machine and in tabulating mechanism, the combination of a carriage, column stops, a stop magazine element, a stop bar element, one of said elements being mounted on said carriage, stop controlling devices for moving said column stops between said elements including a lever member; carriage escapement devices comprising a dog rocker, a key operated universal bar, and connecting devices between said rocker and said universal bar, and means mounted on certain of said connecting devices and projecting into the path 10 of said lever member so as to be operative automatically by said lever member to actuate said dog rocker.
34. In a typewriting machine and in tabulating mechanism, the combination of tabulator stops, and a stop magazine for inclosing said stops, said magazine being composed of two parts detachably secured together.
35. In a typewriting machine and in tabulating mechanism, the combination of tabulator stops, and a stop magazine for inclosing said stops, said magazine consisting substantially of two U-shaped parts, said parts being interseated and detachably connected by screws.
36. In a typewriting machine and in tabulating mechanism, the combination of tabulator stops, and a stop magazine for inclosing said stops, said magazine consisting substantially of two U-shaped parts, said parts being interseated and detachably connected by screws, one of said parts being
- provided with a cylindrical extension at one end and with a head provided with 50 guide ways at the other end.
37. In a typewriting machine and in tabulating mechanism, the combination of tabulator stops, and a stop magazine for inclosing said stops, said magazine consisting substantially of two U-shaped parts, said parts being interseated and detachably connected by screws, one of said parts being provided with a cylindrical extension at one end and with a head provided with 55 guide ways at the other end and also being provided with slotted ears for securing the magazine to the machine frame.
38. In a typewriting machine and in tabulating mechanism, the combination of tabulator stops, a stop magazine for inclosing 60 said stops, said magazine being composed of two parts detachably secured together, one of said parts being provided with an open cylindrical portion, and a plug driven into said portion and carrying a support or 65 rod on which the stops within the magazine are supported.
39. In a stop transferring mechanism, the combination of two opposing springs, and a key which at one part of its stroke stores 70 power in one of said springs and during another part of its stroke releases said power to cause the transference of a stop, leaving the other spring free to restore the operating parts.
40. In a stop transferring mechanism, a spring for causing transference of a stop, said spring being stored with power during one part of a key stroke and then released to exert its power at a further portion of said stroke.

Signed at Syracuse, in the county of Onondaga, and State of New York this 20th day of August, A. D. 1913.

HERBERT H. STEELE.
